UNITED STATES PATENT OFFICE.

CHARLES LE G. FORTESCUE, OF PITTSBURGH, PENNSYLVANIA, ASSIGNOR TO WESTINGHOUSE ELECTRIC & MANUFACTURING COMPANY, A CORPORATION OF PENNSYLVANIA.

ELECTRICAL PROTECTIVE SYSTEM.

Application filed December 17, 1925. Serial No. 75,994.

My invention relates to electrical protective systems and it has particular relation to systems for minimizing the effect of inductive interference in telephone, signal or other intelligence-transmission circuits paralleling power circuits.

An object of my invention is the minimizing of acoustic shock in telephone receivers by so dissipating the energy transmitted 10 through the telephone circuit that the receivers are not affected thereby.

Another object of my invention is to protect telephone or other signal circuits and apparatus from undue voltage strains.

It is now well understood that in a power system, for example, operating with a solidly grounded neutral, an abnormal condition, such as a flashover to ground, causes a single-phase current to flow in a circuit comprising 20 the grounded conductor, the fault, the ground circuit and the neutral connection. This flow of current may be sufficient to induce a high voltage in an adjacent intelligence-transmission circuit, the magnitude of 25 which depends upon the value of the inducing current, the proximity of the power and intelligence-transmission circuits, conditions of the soil, the impedance of the telephone circuit and, of course, the duration of the 30 disturbance.

The interference effect of the voltage thus induced in a telephone circuit, for example, varies with the magnitude thereof and the effectiveness of the telephone protective apparatus. In many cases, severe magnetic 35 disturbance is produced in the telephone receivers with a corresponding "acoustic shock" to the operators. Excessive voltage may also cause failure of insulation or other wise 40 effect relays and signal devices.

Various devices have been employed, such as carbon-block protectors, for discharging the induced energy through a grounded circuit. The effectiveness of such devices is 45 limited by their inherent defects. It has been found that carbon-block protectors inevitably fail to ground both sides of the telephone circuit simultaneously, whereupon severe vibrations are set up in the telephone 50 receivers, which effect has been termed "acoustic shock."

In order to overcome this faulty operation of protectors of the above-indicated character, one method now employed comprises

the connection of a drainage coil between 55 the telephone conductor with the neutral or midpoint of the coil grounded. This connection is objectionable in that it affords an electrical connection between the different lines of the telephone circuit and thereby 60 increases the transmission losses and interferes with the balancing and testing of the telephone or signal lines.

In accordance with my invention, I employ a drainage coil that is normally open- 65 circuited; that is, it is not normally connected in circuit with the telephone conductors.

My invention will be best understood by reference to the accompanying drawing, in 70 which the single figure is a diagrammatic representation of circuits and apparatus embodying my invention.

Referring to the drawing, the power circuit, comprising line conductors 1, 2 and 3, 75 is illustrated as a polyphase circuit having a grounded neutral connection through a conductor 4. Adjacent to and paralleling the power conductors, is a telephone circuit, for example, comprising conductors 5 and 6 and 80 a telephone terminal equipment including a receiver 7. At a point along the telephone circuit is installed protective apparatus comprising a drainage coil 8 wound in two substantially equal parts, or sections, 9 and 10, 85 upon a common magnetic core 11.

In accordance with this construction, a voltage induced in winding 9 will induce a corresponding potential in winding 10. These windings are respectively connected 90 through suitable gap protectors 12 and 13 to line conductors 5 and 6. At another point along the telephone line similar protective apparatus is installed comprising a drainage coil 14 and spark gaps 15 and 16. The coil 95 14 has two sections 18 and 19 that are wound on a common core 20.

Upon the occurrence of a fault in power conductor 3, for example, at the point 17, a single-phase circuit is established comprising power-line conductor 3, fault 17, the ground circuit and neutral conductor 4. The magnetizing current flowing in this single-phase circuit induces a voltage, in the telephone conductors 5 and 6, which may be 100 presumed to be of sufficient value to break down and thereby establish a circuit through the spark-gap protector 12, the drainage coil 105

winding 9 to ground, and thence through a portion 19 of coil 14 and gap 16.

It will be evident that the current flowing in windings 9 and 19 immediately induces a current at a corresponding high voltage in windings 10 and 18, respectively, and results in break-downs across the protectors 13 and 15. The break-down of protectors 13 and 15 is substantially simultaneous with the break-down of protectors 12 and 16, the difference in time being so small that the mechanical inertia of the diaphragm of the receiver 7 does not permit of an appreciable vibration therein within the time interval required for dissipating the energy from the telephone circuit to ground.

In a long telephone system, it may be advisable to install more than two drainage coils. It has also been found advantageous to employ a spark-gap structure of the character described in Patent No. 1,509,497 to Joseph Slepian, which device produces a brush discharge between its confronting surfaces and a uniform discharge of energy.

I have also found it advantageous to connect an additional spark gap arrester across the terminals of each drainage coil, as illustrated at 21 and 22. In the event of a power conductor falling on a telephone line, a very high voltage would be impressed on the drainage coils except for the fact that the protectors 21 and 22 will break down and so limit the impressed voltage to a safe value, thus preventing damage to the coils.

Various modifications may be made in my invention and its application, as will be readily appreciated by those skilled in the art. I desire, therefore, that my invention shall be limited only in accordance with the scope of the appended claims.

I claim as my invention:

1. In a protective system for an intelligence-transmission circuit running adjacent to a power circuit, the combination with a pair of conductors, of a normally open-circuited drainage coil, means for grounding one point of said coil, and means for connecting said coil between said conductors under predetermined voltage conditions.

2. In a protective system for telephone conductors running adjacent to a power circuit, the combination with a pair of telephone conductors, of a pair of normally open-circuited drainage coils means for grounding the junction point of said coils, and means for connecting said coils between said conductors under predetermined voltage conditions.

3. In a protective system for telephone conductors running adjacent to a power cir-

cuit, the combination with a pair of telephone conductors of a normally open-circuited two-part drainage coil, said parts being inductively related, means for grounding the mid-point of said coil, and means for connecting said coil between said conductors under predetermined voltage conditions.

4. In a protective system for telephone conductors running adjacent to a power circuit, the combination with a pair of telephone conductors, of a normally open-circuited drainage coil, means for grounding the mid-point of said coil, and means comprising a spark gap arrester for connecting said coil between said conductors under predetermined voltage conditions.

5. In a protective system for telephone conductors running adjacent to a power circuit, the combination with a pair of telephone conductors, of a normally open-circuited two-part drainage coil, means for grounding the junction-point of said coil parts, and means comprising a spark gap arrester for connecting said coil between said conductors under predetermined voltage conditions.

6. In a protective system for telephone conductors running adjacent to a power circuit, the combination with a pair of telephone conductors, of a normally open-circuited two-part drainage coil, said parts being inductively related, means for grounding the mid-point of said coil, and means comprising a spark gap arrester for connecting said coil between said conductors under predetermined voltage conditions.

7. In a protective system for an intelligence-transmission circuit running adjacent to a power circuit, the combination with a pair of conductors, of a normally open-circuited drainage coil, means for grounding the mid-point of said coil, means for connecting said coil between said conductors under predetermined voltage conditions, and means for limiting the voltage across said coil.

8. In a protective system for an intelligence-transmission circuit running adjacent to a power circuit, the combination with a pair of conductors, of a normally open-circuited drainage coil, means for grounding the mid-point of said coil, means comprising a spark gap arrester for connecting said coil between said conductors under predetermined voltage conditions, and means comprising a spark gap for shunting said coil.

In testimony whereof, I have hereunto subscribed my name this 8th day of December, 1925.

CHARLES LE G. FORTESCUE.
